A. W. HULL

ELECTRON DISCHARGE APPARATUS

Filed Sept. 8, 1921

Inventor:
Albert W. Hull,
by *Albert W. Hull*
His Attorney.

UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

ELECTRON-DISCHARGE APPARATUS.

Application filed September 8, 1921. Serial No. 499,293.

To all whom it may concern:

Be it known that I, ALBERT W. HULL, a citizen of the United States, residing at Schenectady, county of Schenectady, State of New York, have invented certain new and useful Improvements in Electron-Discharge Apparatus, of which the following is a specification.

My present invention relates to electron discharge apparatus and more particularly to the well-known type of apparatus in which current is carried across an evacuated space chiefly by means of electrons without any substantial gas ionization effects being produced or influencing the flow of current.

The object of my invention is to provide an improved apparatus of the type mentioned and method of operating the same which will possess marked advantages over apparatus previously employed.

In carrying my invention into effect I employ preferably a three electrode device having the usual electron emitting cathode, anode and controlling grid enclosed in an evacuated receptacle. The electrodes of this device are preferably arranged in substantially circular symmetry with respect to one another. In addition I provide means for producing a magnetic field in the space between the electrodes in a direction at a right angle to the paths of the electrons. This means for producing the magnetic field may be in the form of a coil surrounding the receptacle and this coil may be supplied with current from the output circuit of the device.

The current through the device may be controlled by means of the grid electrode to perform any of the functions for which a device of the type mentioned is adapted. When the magnetic field produced is properly proportioned the device may possess several operating advantages over three electrode devices of similar type as previously operated. When such devices are employed as amplifiers the degree of amplification which may be obtained depends upon the slope of the curve representing the relation between grid potential and output current. By the use of a magnetic field control in conjunction with the electrostatic field control the slope of this curve may, over a well defined operating range of

grid potential, be greatly increased over its value in the absence of the magnetic field.

In the usual three-electrode device current continues to flow between cathode and anode even when the grid potential becomes negative and the current decreases rather slowly as the negative grid potential is increased to a point at which no current will flow. By the use of a magnetic field in accordance with my invention the current flow may be caused to decrease to substantially zero very quickly even when the grid potential is positive. This permits of the operation of the device without the usual biasing potential on the grid and permits of the substantial interruption of current at desired periods in an efficient manner.

When the three electrode device is operated as a detector and the asymmetry of the current curve is utilized to secure the detector action normal operation takes place at a point where there is a marked change in the curvature of the characteristic current curve. The more abrupt this change in curvature, the more efficient the operation of the device. The increase in the slope of the characteristic curve referred to above also is accompanied by more abrupt changes in the curvature than occur when the device is operated without a magnetic field thus rendering the device more suitable as a detector.

The sharp cut off in the current which has already been mentioned may be employed to advantage when the device is utilized for producing oscillations as it is desirable in this case that current be supplied to the oscillating circuit only during certain portions of the cycle.

It is well known that the general effect of a magnetic field at a right angle to the path of a moving electron is to deflect the electron causing it to move in a spiral path instead of a straight path. The first result, therefore, of the application of a magnetic field in the manner described is to cause more of the electrons to strike the grid than would be the case in the absence of the magnetic field. This effect is especially large in case the grid is made of slats as described in my co-pending application, Serial No. 472,139, filed May 24, 1921.

If the potentials applied to the elec-

trodes are properly chosen each electron which strikes the grid may produce several secondary or impact electrons which will travel to the more positive anode. As a result the current produced in the output circuit may be several times the current which would be produced therein by the primary electrons emitted by the cathode. When the device is employed as an amplifier this phenomenon may be utilized to increase the amplification obtained, and when it is used as an oscillator the amplitude of the oscillations produced may be greatly increased by reason of this phenomenon. In most cases the emission of secondary electrons from the grid will preferably be of great enough magnitude to produce a negative resistance characteristic in the grid circuit. This characteristic may be utilized to increase the amplification which may be obtained and also for generating oscillations. In the latter case the potential of the grid is caused to vary in accordance with the oscillations produced and greatly amplified oscillations may be supplied from the output circuit.

The novel features which I believe to be characteristic of my invention are set forth with particularity in the appended claims. My invention itself, however, will best be understood by reference to the following description taken in connection with the accompanying drawing in which Fig. 1 shows diagrammatically the application of my invention to an amplifying system; Fig. 2 shows diagrammatically its application to a system for producing oscillations for radio transmission, and Figs. 3, 4 and 5 show characteristic operating curves of devices with which my invention is employed.

As indicated in the drawing, I provide an electron discharge device having a linear filamentary cathode 1 adapted to be heated to incandescence by a battery 2, or other source of current, a cylindrical grid 3 surrounding the cathode, and a cylindrical anode 4 surrounding the grid and cathode. The grid and anode are preferably arranged in circular symmetry about the cathode and the electrodes are all enclosed in an evacuated receptacle 5. An input circuit between cathode and grid includes a coil 6 which in Fig. 1 forms the secondary of a transformer to the primary 7 of which the currents to be amplified are supplied. An output circuit between cathode and anode includes a source of current 8, an output coil 9 and a second magnetizing coil 10 which preferably surrounds the receptacle 5 and the major axis of which is preferably substantially coincident with the axis of symmetry of the electrodes. The coil 10 is shunted by a condenser 11 of large capacity. In Fig. 1 the output coil is coupled to a coil 12 which is included in a

circuit to which amplified currents are supplied. In Fig. 2 the output coil 9 is coupled to a coil 13 in an antenna 14 to which oscillations may be supplied for transmitting purposes. Oscillations may be generated in the system by means of a feed back connection between output and input circuits which comprises coupling coils 15, and 16. In case it is desired to produce a negative resistance in the grid circuit and employ this characteristic for the production of oscillations, the feed back connection may be omitted and a condenser 17 may be inserted in the input circuit in shunt to coil 6, the frequency of the oscillations thus produced being determined by the tuning of the resonant circuit formed by coil 6 and condenser 17. In this case it is necessary to first impress a positive charge upon the grid before oscillations will start. This may be accomplished by connecting one terminal of the condenser 17 by the dotted line connection 18 indicated to a point in the battery 8 instead of directly to the cathode.

In Fig. 3 I have shown curves representing the relation between grid potential and anode current under different conditions of operation. Curve A is a typical characteristic of a three-electrode device as ordinarily operated, and curve B shows a corresponding characteristic when a magnetic field is employed in the manner described. It will be observed from curve B that the anode current instead of decreasing gradually as the grid becomes more negative, decreases very rapidly as the grid becomes negative and reaches a substantially zero value at a much lower negative grid potential than in the case where the magnetic field is absent. The portion of the curve B between the points e_1 and e_2 is much steeper than any portion of curve A and therefore a much greater degree of amplification may be obtained with the device over this range than when the device is operated without the magnetic field. It should also be noted that at both points e_1 and e_2 there are much more abrupt changes in the curvature of the characteristic than are found on curve A. Either of these points therefore may be advantageously employed for operating the device as a detector.

The value of the grid potential at which the flow of current will be interrupted depends in any particular device upon the strength of the magnetic field. In general, the stronger the magnetic field the more positive or less negative the grid potential at which cut-off occurs. In general also the stronger the magnetic field the steeper the slope of the characteristic curve. In Fig. 4 I have indicated the characteristic curve in a case where the magnetic field is strong enough to cut off the current when there is a fairly high positive potential on the grid.

This adjustment may be employed advantageously when the device is utilized for producing oscillations. The curve C in Fig. 4 shows the time relation and amplitude of the grid potential when oscillations are produced. It will be seen from this curve taken in conjunction with curve B that current is supplied to the anode only during the intervals represented by the shaded portions of curve C. It will be noted that with the arrangement shown and described it is not necessary to employ any grid leak or biasing battery to adjust the normal grid potential but that efficient operation may be obtained by regulating the strength of the magnetic field to shorten the time in each cycle of the grid potential during which current will flow instead of producing a similar effect by means of a grid bias. In case the grid oscillations are properly phased with respect to the oscillations of the anode potential this arrangement will result in a greater efficiency of operation of the system than when current is supplied to the anode during the greater part of the cycle of grid potential.

In the curves shown in Figs. 3 and 4, it is assumed that there is not sufficient secondary emission produced from the grid to produce any appreciable effect upon the current in the output circuit. The effect of large secondary emission from the grid is indicated in Fig. 5. In this figure curve A represents as before the characteristic in the absence of a magnetic field and curve B represents the characteristic with a magnetic field. Curve D shows the relation between grid current and grid potential, this current being negative or in the opposite direction to the usual grid current by reason of the high secondary emission. Curve B indicates the resultant current in the output circuit produced by the primary electrons which reach the anode and the secondary or impact electrons from the grid which flow to the anode. By reason of the high secondary emission the current which may be supplied to the output circuit is much greater than that which would be supplied by primary emission alone in the absence of a magnetic field. It will be apparent that by reason of this effect the amplitude of oscillations supplied by the output circuit may be greatly increased over their amplitude in the absence of a magnetic field.

In the operation of three electrode devices as oscillators, difficulty has been experienced from the destruction of tubes by heavy rushes of current due to accidental short circuiting of the load. Such heavy currents are probably due to a combination of causes among which are the fact that when the load is wholly or partially short circuited the anode potential becomes very much higher than normal and causes a great

increase in the current through the tube. This increase of current is prevented in the arrangement shown in Fig. 2 by the series magnetic field.

The characteristic curves illustrated show the effect of a constant magnetic field and if desired, this constant magnetic field may be provided by a separate constant source of energy. When, however, this device is employed as an amplifier of alternating current or as an oscillator, it will usually be more convenient to utilize the series coil 10 for producing the magnetic field. The field produced in this way will be substantially constant by reason of the large capacity condenser 11 in shunt to coil 10. It may also in some cases be desirable to supply a portion of the magnetic field from a separate source of energy and the remainder by means of a series coil.

In some cases when the device is employed as an oscillator it may be desirable to make the condenser 11 adjustable and tune the loop circuit 10, 11 to the frequency of the oscillations to be produced. While in this case the field will be variable an even sharper cut off in the output current may be obtained. In this case the circuit 10, 11 may constitute the only oscillating circuit in the system and may constitute the work circuit as, for example, by replacing the condenser 11 by the capacity of the antenna.

What I claim as new and desire to secure by Letters Patent of the United States, is:—

1. The combination with an electron discharge device having a cathode, an anode and a controlling grid, said electrodes being arranged in substantially circular symmetry with respect to one another, of a circuit between cathode and anode, means for varying the potential of said grid, and means for producing by current flowing in the circuit between cathode and anode a magnetic field in the space between said electrodes, the strength of the magnetic field being so adjusted as to greatly increase over a predetermined operating range the slope of the curve showing the relation between grid voltage and anode current over its slope in the absence of such magnetic field.

2. The combination with an electron discharge device having a cathode, an anode and a controlling grid, of a circuit between cathode and anode, means for varying the potential of said grid and means for producing by current flowing in the circuit between cathode and anode, a magnetic field in the space between said electrodes, the strength of the magnetic field being so adjusted as to greatly increase over a predetermined operating range the slope of the curve showing the relation between grid voltage and anode current over its slope in the absence of such magnetic field.

3. The combination with an electron dis-

- charge device having a cathode, an anode and a controlling grid interposed between said cathode and anode, said electrodes being arranged in substantially circular symmetry with respect to one another, of a circuit between cathode and anode, means for varying the potential of said grid, and means for producing a magnetic field in the space between said electrodes, the strength of the magnetic field being so adjusted as to greatly increase over a predetermined operating range the slope of the curve showing the relation between grid voltage and anode current over its slope in the absence of such magnetic field.
4. The combination with an electron discharge device having a cathode, an anode and a controlling grid, said electrodes being arranged in substantially circular symmetry with respect to one another of a circuit between cathode and anode, means for varying the potential of said grid and a magnetizing coil surrounding said electrodes which is included in the circuit between cathode and anode, said coil being so proportioned that the magnetic field produced thereby will greatly increase over a given operating range the slope of the curve showing the relation between grid voltage and anode current over its slope in the absence of such magnetic field.
5. The combination with an electron discharge device having a cathode, an anode and a controlling grid, said electrodes being arranged in substantially circular symmetry with respect to one another, of a circuit between cathode and anode, means for varying the potential of said grid, and a magnetizing coil surrounding said electrodes which is included in the circuit between cathode and anode, and the major axis of which is substantially coincident with the axis of symmetry of the electrodes, said coil being so proportioned that the magnetic field produced thereby greatly increases over a given operating range the slope of the curve showing the relation between grid voltage and anode current over its slope in the absence of such magnetic field.
6. The combination with an electron discharge device having a cathode, an anode, and a controlling grid, said electrodes being arranged in substantially circular symmetry with respect to one another of a circuit between cathode and anode, means for varying the potential of said grid, a magnetizing coil surrounding said electrodes which is included in the circuit between cathode and anode, said coil being so proportioned that the magnetic field produced thereby greatly increases over a given operating range the slope of the curve showing the relation between grid voltage and anode current over its slope in the absence of such magnetic field, and a condenser in shunt to said coil.
7. The combination with an electron discharge device having a cathode, an anode, and a controlling grid, said electrodes being arranged in substantially circular symmetry with respect to one another of a circuit between cathode and anode, means for varying the potential of said grid, a magnetizing coil surrounding said electrodes which is included in the circuit between cathode and anode, said coil being so proportioned that the magnetic field produced thereby greatly increases over a given operating range the slope of the curve showing the relation between grid voltage and anode current over its slope in the absence of such magnetic field, and a condenser in shunt to said coil, said condenser in combination with said magnetizing coil forming a circuit which is resonant to the frequency of the variations in grid potential.
8. The combination with an electron discharge device having a cathode, an anode, and a controlling grid, of a circuit between cathode and anode, means for varying the potential of said grid, a magnetizing coil surrounding said electrodes which is included in the circuit between cathode and anode, said coil being so proportioned that the magnetic field produced thereby greatly increases over a given operating range the slope of the curve showing the relation between grid voltage and anode current over its slope in the absence of such magnetic field, and a condenser in shunt to said coil, said condenser in combination with said magnetizing coil forming a circuit which is resonant to the frequency of the variations in grid potential.
9. The combination with an electron discharge device having a cathode, an anode, and a controlling grid, said electrodes being arranged in substantially circular symmetry with respect to one another, of a circuit between cathode and anode, means for varying the potential of said grid, a magnetizing coil surrounding said electrodes which is included in the circuit between cathode and anode, and the major axis of which is substantially coincident with the axis of symmetry of the electrodes, said coil being so proportioned that the magnetic field produced thereby greatly increases over a given operating range the slope of the curve showing the relation between grid voltage and anode current over its slope in the absence of such magnetic field, and a condenser in shunt to said coil.
10. The combination with an electron discharge device having a cathode, an anode, and a controlling grid, said electrodes being arranged in substantially circular symmetry with respect to one another of a circuit between cathode and anode, means for varying the potential of said grid, and a magnetizing coil surrounding said electrodes

- which is supplied with current from the circuit between cathode and anode, said coil being so proportioned that the magnetic field produced thereby greatly increases over a given operating range the slope of the curve showing the relation between grid voltage and anode current over its slope in the absence of such magnetic field.
11. The combination with an electron discharge device having a cathode, an anode, and a controlling grid, said electrodes being arranged in substantially circular symmetry with respect to one another, of a circuit between cathode and anode, means for varying the potential of said grid, a magnetizing coil surrounding said electrodes which is supplied with current from the circuit between cathode and anode, said coil being so proportioned that the magnetic field produced thereby greatly increases over a given operating range the slope of the curve showing the relation between grid voltage and anode current over its slope in the absence of such magnetic field, and a condenser in shunt to said coil.
12. The combination with an electron discharge device having a cathode, an anode and a controlling grid interposed between said cathode and anode, of means for varying the potential of said grid, an output circuit connected between said cathode and said anode and means for producing a magnetic field in the space between said electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field.
13. The combination with an electron discharge device having a cathode, an anode and a controlling grid, of means for varying the potential of said grid, an output circuit connected between said cathode and said anode and means for producing by the current flowing in said output circuit a magnetic field in the space between said electrodes said device being so constructed and the magnetic field produced being of such strength that over a predetermined operating range of grid potential the current supplied by said output circuit will, due to the emission of impact electrons from the grid, be greatly increased over its value in the absence of the magnetic field.
14. The combination with an electron discharge device having a cathode, an anode and a controlling grid interposed between said cathode and anode, said electrodes being arranged in substantially circular symmetry with respect to one another, of means for varying the potential of said grid, an output circuit connected between said
- cathode and said anode and means for producing a magnetic field in the space between said electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field.
15. The combination with an electron discharge device having a cathode, an anode, and a controlling grid, said electrodes being arranged in substantially circular symmetry with respect to one another, of means for varying the potential of said grid, an output circuit connected between said cathode and said anode and a coil surrounding said electrodes which is included in the output circuit for producing a magnetic field in the space between said electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field.
16. The combination with an electron discharge device having a cathode, an anode and a controlling grid, said electrodes being arranged in substantially circular symmetry with respect to one another, of means for varying the potential of said grid, an output circuit connected between said cathode and said anode, and a coil surrounding said electrodes which is included in the output circuit for producing a magnetic field in the space between said electrodes the major axis of said coil being substantially coincident with the axis of symmetry of the electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field.
17. The combination with an electron discharge device having a cathode, an anode and a controlling grid, said electrodes being arranged in substantially circular symmetry with respect to one another, of means for varying the potential of said grid, an output circuit connected between said cathode and said anode and a coil surrounding said electrodes which is supplied with current from the output circuit for producing a magnetic field in the space between said electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field.
18. The combination with an electron discharge device having a cathode, an anode and a controlling grid, said electrodes being arranged in substantially circular symmetry with respect to one another, of means for varying the potential of said grid, an output circuit connected between said cathode and said anode and a coil surrounding said electrodes which is supplied with current from the output circuit for producing a magnetic field in the space between said electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field.

- terminated operating range of grid potential the current supplied by said output circuit will, due to the emission of impact electrons from the grid, be greatly increased over its 6 value in the absence of the magnetic field.
18. The combination with an electron discharge device having a cathode, an anode and a controlling grid, said electrodes being arranged in substantially circular symmetry 10 with respect to one another of means for varying the potential of said grid, an output circuit connected between said cathode and said anode and a coil surrounding said electrodes which is supplied with current from 15 the output circuit for producing a magnetic field in the space between said electrodes, said device being so constructed and the magnetic field produced being of such strength that over a predetermined operating range of grid potential the current supplied by said output circuit will, due to the emission of impact electrons from the grid, be greatly increased over its value in the absence of the magnetic field, and a condenser 20 in shunt to said coil, said condenser in combination with said magnetizing coil forming a circuit which is resonant to the frequency of the variations in grid potential.
19. The combination with an electron discharge device having a cathode, an anode and a controlling grid, of means for varying the potential of said grid, an output circuit connected between said cathode and said anode, means for producing a magnetic 30 field in the space between said electrodes, and means independent of said magnetic field for producing oscillations in said output circuit, said device being so constructed and the magnetic field produced being of 35 such strength that over a predetermined operating range of grid potential the amplitude of the oscillations supplied by said output circuit, will, due to the emission of impact electrons from the grid, be greatly increased over their amplitude in the absence of the magnetic field.
20. The combination with an electron discharge device having a cathode, an anode and a controlling grid, of means for varying the potential of said grid, an output circuit connected between said cathode and said anode, means for producing by the current flowing in said output circuit a magnetic field in the space between said electrodes, and means independent of said magnetic field for producing oscillations in said output circuit, said device being so constructed and the magnetic field produced being of 50 such strength that over a predetermined operating range of grid potential the amplitude of the oscillations supplied by said output circuit will, due to the emission of impact electrons from the grid, be greatly increased over their amplitude in the absence of the magnetic field.
21. The combination with an electron discharge device having a cathode, an anode and a controlling grid, said electrodes being arranged in substantially circular symmetry with respect to one another, of means for varying the potential of said grid, an output circuit connected between said cathode and said anode, means for producing by the current flowing in said output circuit a magnetic field in the space between said electrodes and means independent of said magnetic field for producing oscillations in said output circuit, said device being so constructed and the magnetic field produced being of such strength that over a predetermined operating range of grid potential the amplitude of the oscillations supplied by said output circuit, will, due to the emission of impact electrons from the grid, be greatly increased over their amplitude in the absence of the magnetic field.
22. The combination with an electron discharge device having a cathode, an anode and a controlling grid, said electrodes being arranged in substantially circular symmetry with respect to one another, of means for varying the potential of said grid, an output circuit connected between said cathode and said anode, a coil surrounding said electrodes which is included in the output circuit for producing a magnetic field in the space between said electrodes and means independent of said magnetic field for producing oscillations in said output circuit, said device being so constructed and the magnetic field produced being of such strength that over a predetermined operating range of grid potential the amplitude of the oscillations supplied by said output circuit will, due to the emission of impact electrons from the grid, be greatly increased over their amplitude in the absence of the magnetic field.
23. The combination with an electron discharge device having a cathode, an anode and a controlling grid, of means for varying the potential of said grid, an output circuit connected between said cathode and said anode, a coil surrounding said electrodes which is included in the output circuit for producing a magnetic field in the space between said electrodes, and means independent of said magnetic field for producing oscillations in said output circuit, said device being so constructed and the magnetic field produced being of such strength that over a predetermined operating range of grid potential the amplitude of the oscillations supplied by said output circuit will, due to the emission of impact electrons from the grid, be greatly increased over their amplitude in the absence of the magnetic field, and a condenser in shunt to said coil, said condenser in combination with said magnetizing coil forming a circuit which is resonant to the

frequency of the variations in grid potential.

24. The combination with an electron discharge device having a cathode, an anode and a controlling grid, said electrodes being arranged in substantially circular symmetry with respect to one another, of means for varying the potential of said grid, an output circuit connected between said cathode and 10 said anode, a coil surrounding said receptacle which is supplied with current from the output circuit for producing a magnetic field in the space between said electrodes, and means independent of said magnetic field for 15 producing oscillations in said output circuit, said device being so constructed and the magnetic field produced being of such strength that over a predetermined operating range of grid potential the amplitude of the 20 oscillations supplied by said output circuit will, due to the emission of impact electrons from the grid, be greatly increased over their amplitude in the absence of the magnetic field.
25. The combination with an electron discharge device having a cathode, an anode and a controlling grid, said electrodes being arranged in substantially circular symmetry with respect to one another, of means for 25 varying the potential of said grid, an output circuit connected between said cathode and said anode, a coil surrounding said electrodes which is included in the output circuit for producing a magnetic field in the 30 space between said electrodes, the major axis of said coil being substantially coincident with the axis of symmetry of the electrodes, and means independent of said magnetic field for producing oscillations in said output circuit, said device being so constructed and the magnetic field produced being of 35 such strength that over a predetermined operating range of grid potential the amplitude of the oscillations supplied by said output circuit will, due to the emission of impact electrons from the grid, be greatly increased over their amplitude in the absence 40 of the magnetic field.
26. The combination with an electron dis- 45

charge device having a cathode, an anode and a controlling grid of an oscillating circuit connected between said cathode and said grid, an output circuit connected between said cathode and said anode, and a coil surrounding said electrodes which is supplied with current from said output circuit, said device being so constructed and the magnetic field produced by said coil being of such value that an emission of impact electrons from said grid will be produced of sufficient amount to produce a negative resistance in the circuit between cathode and grid and cause the generation of oscillations in the oscillating circuit.

27. The combination with an electron dis-

charge device having a cathode, an anode and a controlling grid, said electrodes being arranged in substantially circular symmetry with respect to one another, of an oscillating circuit connected between said cathode and said grid, an output circuit connected between said cathode, and said anode, and a coil surrounding said electrodes which is supplied with current from said output circuit, said device being so constructed and the magnetic field produced by said coil being of such value that an emission of impact electrons from said grid will be produced of sufficient amount to produce a negative resistance in the circuit between cathode and grid and cause the generation of oscillations in the oscillating circuit.

28. The combination with an electron discharge device having a cathode, an anode and a controlling grid, said electrodes being arranged in substantially circular symmetry with respect to one another, of an oscillating circuit connected between said cathode and said grid, an output circuit connected between said cathode and said anode, and a coil surrounding said electrodes which is supplied with current from said output circuit, the major axis of said coil being substantially coincident with the axis of symmetry of said electrodes, said device being so constructed and the magnetic field produced by said coil being of such value that an emission of impact electrons from said grid will be produced of sufficient amount to produce a negative resistance in the circuit between cathode and grid and cause the generation of oscillations in the oscillating circuit.

29. The combination with an electron discharge device having a cathode, an anode and a controlling grid, of a circuit between cathode and anode, means for impressing an alternating potential on said grid and means for producing by current flowing in the circuit between cathode and anode a magnetic field in the space between said electrodes, the strength of the magnetic field being so adjusted as to greatly shorten the time in each cycle of grid potential during which current will flow to the anode.

30. The combination with an electron discharge device having a cathode, an anode and a controlling grid interposed between said cathode and anode said electrodes being arranged in substantially circular symmetry with respect to one another, of a circuit between cathode and anode, means for impressing an alternating potential on said grid, and means for producing a magnetic field in the space between said electrodes, the strength of the magnetic field being so adjusted as to greatly shorten the time in each cycle of grid potential during which current will flow to the anode.

31. The combination with an electron dis- 130

- and a controlling grid, said electrodes being arranged in substantially circular symmetry with respect to one another, of a circuit between cathode and anode, means for impressing an alternating potential on said grid, and means for producing by current flowing in the circuit between cathode and anode a magnetic field in the space between said electrodes, the strength of the magnetic field being so adjusted as to greatly shorten the time in each cycle of grid potential during which current will flow to the anode.
32. The combination with an electron discharge device having a cathode, an anode and a controlling grid, said electrodes being arranged in substantially circular symmetry with respect to one another of a circuit between cathode and anode, means for impressing an alternating potential on said grid and a magnetizing coil surrounding said electrodes which is included in the circuit between cathode and anode, said coil being so proportioned that the magnetic field produced thereby will greatly shorten the time in each cycle of grid potential during which current will flow to the anode.
33. The combination with an electron discharge device having a cathode, an anode, and a controlling grid, said electrodes being arranged in substantially circular symmetry with respect to one another, of a circuit between cathode and anode, means for impressing an alternating potential on said grid, a magnetizing coil surrounding said electrodes which is included in the circuit between cathode and anode, said coil being so proportioned that the magnetic field produced thereby will greatly shorten the time in each cycle of grid potential during which current will flow to the anode.
34. The method of operating an electron discharge device having a cathode, an anode and a controlling grid which consists in producing a flow of electrons between cathode and anode, impressing a variable potential upon the grid and producing by means of current carried by the electron stream a magnetic field in the space between the electrodes of sufficient magnitude to greatly increase over a predetermined operating range the slope of the curve representing the relation between anode current and grid potential over its slope in the absence of such magnetic field.
35. The method of operating an electron discharge device having a cathode, an anode and a controlling grid which consists in producing a flow of electrons between cathode and anode, impressing a variable potential upon the grid and producing a magnetic field in the space between the electrodes of sufficient magnitude to greatly increase over a predetermined operating range the slope of the curve representing the relation between anode current and grid potential over

its slope in the absence of such magnetic field.

36. The method of operating an electron discharge device having a cathode, an anode and a controlling grid and an output circuit which consists in producing a flow of electrons between cathode and anode, impressing a variable potential upon the grid, producing a magnetic field in the space between the electrodes of such a value and in such a direction that it will cause an increase in the emission of impact electrons from the grid, and thereby increase over a predetermined operating range of grid potential the current flowing in the output circuit over the value of such current in the absence of a magnetic field.

37. The method of operating an electron discharge device having a cathode, an anode and a controlling grid and an output circuit which consists in producing a flow of electrons between cathode and anode, impressing a variable potential upon the grid, producing by means of current carried by the electron stream a magnetic field in the space between the electrodes of such a value and in such a direction that it will cause an increase in the emission of impact electrons from the grid, and thereby increase over a predetermined operating range of grid potential the current flowing in the output circuit over the value of such current in the absence of a magnetic field.

38. The method of operating an electron discharge device having a cathode, an anode and a controlling grid and an output circuit which consists in producing a flow of electrons between cathode and anode, producing a magnetic field in the space between the electrodes, producing oscillations in the output circuit independently of the action of the magnetic field and controlling the magnetic field in such a way that the amplitude of the oscillations produced in the output circuit will be greatly increased over their amplitude in the absence of the magnetic field.

39. The method of operating an electron discharge device having a cathode, an anode and a controlling grid and an output circuit which consists in producing a flow of electrons between cathode and anode, producing a magnetic field in the space between the electrodes, producing oscillations in the output circuit independently of the action of the magnetic field and controlling the magnetic field in such a way as to produce a large emission of impact electrons from the grid by reason of which the amplitude of the oscillations produced in the output circuit will be greatly increased over their amplitude in the absence of the magnetic field.

40. The method of operating an electron discharge device having a cathode, an anode and a controlling grid and an output cir-

cuit which consists in producing a flow of electrons between cathode and anode, producing a magnetic field in the space between the electrodes to cause a sufficient emission 5 of impact electrons from the grid to produce a negative resistance in a circuit between cathode and grid, utilizing this negative resistance to produce oscillations and thereby vary the potential of the grid 10 and supplying corresponding oscillations of greater amplitude from the output circuit.

41. The method of operating an electron discharge device having a cathode, an anode and a controlling grid which consists in producing a flow of electrons between cathode and anode, impressing an alternating potential upon the grid and producing in the space between the electrodes a magnetic field of sufficient strength to greatly shorten the 15 time in each cycle of grid potential during which current will flow to the anode.

42. The method of operating an electron discharge device having a cathode, an anode and a controlling grid which consists in producing a flow of electrons between cathode and anode, impressing an alternating poten- 20

tial upon the grid and producing in the space between the electrons by means of current carried by the electron stream a magnetic field of sufficient strength to greatly 25 shorten the time in each cycle of grid potential during which current will flow to the anode.

43. The method of operating an electron discharge device having a cathode, an anode and a controlling grid and an output circuit which consists in producing a flow of electrons between cathode and anode, impressing an alternating potential upon the grid and producing in the space between the electrodes a magnetic field of sufficient strength to cause an increase in the emission of impact electrons from the grid and thereby increase over a predetermined range of grid potential the current flowing in the output 35 40 circuit and greatly shorten the time in each cycle of grid potential during which current will flow to the anode.

In witness whereof, I have hereunto set my hand this 7th day of September, 1921.

ALBERT W. HULL.
